UNITED STATES PATENT OFFICE.

ALFRED MANSFIELD, OF VICTORIA, BRITISH COLUMBIA, CANADA.

FUEL-SAVING GRATE FOR RANGES.

Application filed November 22, 1922. Serial No. 602,614.

To all whom it may concern:

Be it known that I, ALFRED MANSFIELD, a resident of the city of Victoria, in the Province of British Columbia, Canada, have invented certain new and useful Improvements in Fuel-Saving Grates for Ranges, of which the following is a specification.

My invention relates to an improvement in supplemental grates which is designed for setting within the fire box of a cooking range and upon the ordinary grate bars, that the fire may be reduced when desired, so that an undue excess of heat is not provided, resulting in a saving of fuel. Therefore, my invention has for its objects the saving of fuel and the effective use of the heat generated by such fuel as is consumed thereon and it consists essentially of a perforated grate with a vertical baffle adjustable thereon and a draught excluding slide covering a portion of the grate as will be more particularly described in the following specification, in which:—

Fig. 1 is a perspective view of my grate shown in place in a range fire box.

Fig. 2 is a longitudinal section.

In the drawings like characters of reference indicate corresponding parts in each figure.

The numeral 1 indicates in general the fuel box of a cooking range, 2 being the rocking grates with which such ranges are usually provided. 3—3 indicates a pair of vertical supports which are rounded at their lower corners as at 4, to permit of the grates 2 being rocked as desired to discharge the ashes from the fire therethrough without disturbing my grate. 5 indicates a horizontal grate having a plurality of apertures 6 arranged in transverse rows therein for the purpose of admitting draft to the fire and also to receive the pins 9. 7 is a baffle plate having a web 8 projecting at right angles to opposite sides of its lower edge to assist the plate in maintaining a vertical position on the grate 5, 9 indicates a plurality of pins projecting downwardly of the web and formed integrally therewith to hold the baffle plate 7 in any desired position against endwise movement of the grate.

10 is a draught plate of similar width to

the grate 5 and preferably greater than one-third of its length having an upstanding and inwardly turned angular member 11 on each of its opposite sides to form a pair of 55 grooves 12, the purpose of which will hereinafter appear.

13 is a slide of approximately similar width to the grate 5 which is designed to slide within the grooves 12 upon the plate 10. 14 indicates upstanding lugs upon the draught plate 10 and the slide 13, by which either may be moved as desired.

Having described the several parts of my invention, I will now briefly explain its use. 65

My grate having been set within the fire box 1, it suffices to determine the length of fire desired and to insert the pins 9 of the baffle plate 7 into any series of apertures 6. 70 The draught plate 10 is then put into position upon the grate 5 and the slide 13 drawn lengthwise of the grooves 12 until the end of the slide reaches the baffle plate 7, when draught is excluded from passing through that portion of the grate which is covered 75 by the draught plate and its slide.

It will thus be seen that I have devised a grate which may be adjusted to reduce the fire space within a range fire box and to divert the draught to the reduced space where- 80 by considerable fuel economy is attained, which is simple in construction and easily installed or removed.

What I claim as my invention is:

1. A device of the character described 85 comprising a pair of relatively wide vertical supporting plates adapted to rest upon and to extend entirely across the grate surface of an ordinary fire box, a supplementary grate carried by said supporting plates 90 and comprising a plate-like body formed with transversely extending rows of spaced openings, a partition member provided with a plurality of spaced depending lugs adapted to be inserted in the openings of one of 95 said rows to secure the partition member in a preselected position on the supplementary grate, and an adjustable damper adapted to be mounted on the supplemental grate to close all of the openings at one side or the 100 other of the partition.

2. A structure, according to claim 1, in

which the damper comprises a pair of superimposed relatively slidable sections, the lower section having opposite marginal portions flanged upwardly and inwardly to provide guides embracing the corresponding marginal portions of the upper section, said damper being adapted to be arranged on the supplemental grate with the guide

flanges of the damper extending longitudinally of the grate.

Dated at Victoria, B. C. this 14th day of November, 1922.

ALFRED MANSFIELD.
